IMPULSE TIMEPIECE

Weyman E. Maxwell, Springfield, Mass., assignor to The Standard Electric Time Company, Springfield, Mass., a corporation of Massachusetts

Application May 19, 1939, Serial No. 274,529

11 Claims. (Cl. 58—26)

This invention relates to improvements in impulse-timepieces (i. e., timepieces having step-by-step movements of their indicating-means), and more especially to means for imparting step-by-step movement to the time-indicating means of impulse-timepiece movements, a group of which are usually simultaneously operated under the remote control of a master clock or the like common to them all.

One of the objects of the present invention is to provide superior and effective means for operating an impulse-timepiece movement in a smoother, quieter and less complicated manner than has heretofore been accomplished in devices of this character.

Another object of the invention is to provide superior electromagnetically-operated mechanism comprising a relatively-small number of parts of simple and effective form to provide a device of this character which is reliable, accurate and noiseless for transmitting to the hour-hand and minute-hand or the like of a secondary timepiece the periodic impulses delivered thereto by a master clock or the like.

Another object of this invention is to provide a superior motor-structure of the eddy-current type whereby the rotary field-effects produced in the rotary armature of said motor-structure by the periodic electrical impulse received from a master clock may be utilized to avoid, in large measure, the use of gearing for transmitting the periodic impulses to the time-indicating means of an impulse-timepiece.

A particular object of the invention is to provide a superior impulse-timepiece movement having a motor-structure of the eddy-current type in which the armature is rotated by the rotary field-effects from a normal "at rest" position through a "first stage" of its operating movement; momentarily arrested in a predetermined position at the end of the said "first stage" of its operating movement; retained in its arrested position until after the motor-structure is deenergized; and finally rotated through a "second stage" movement under a rotational-bias set up in the rotary armature during its "first stage" movement and operating to return the said armature to its normal "at rest" position.

With the above and other objects in view, as will appear to those skilled in the art from the present disclosure, this invention includes all features in the said disclosure which are novel over the prior art.

In the accompanying drawings, in which one

mode of carrying out the present invention is shown for illustrative purposes:

Fig. 1 is a view in rear elevation of an impulse-timepiece movement constructed in accordance with the present invention;

Fig. 2 is a top plan view of the same;

Fig. 3 is a view in side elevation thereof with the parts shown in the relative positions due to them immediately prior to the deenergizing of the motor-structure;

Fig. 4 is a view in side elevation similar to Fig. 3, but showing the several parts in their normal "at rest" positions in the interval between electrical impulses;

Fig. 5 is a perspective view of the magnetically-operated armature-stop lever;

Fig. 6 is a perspective view of the rotary armature, detached;

Fig. 7 is a view in side elevation of a modified form of the invention; and

Fig. 8 is a perspective view of the rotary armature of the embodiment shown in Fig. 7.

In the embodied form of the invention shown in Figs. 1 to 6 inclusive, of the drawings for purposes of illustration, the movement-frame of the impulse-timepiece movement is generally designated by the reference character 10. The said movement-frame 10 supports an eddy-current motor-structure comprising a field-structure 11 which is generally designated by the reference character 11. Suitably constructed and arranged to be operated electromagnetically by the field-structure 11 is a rotary armature, formed of aluminum or other suitable material 35 providing eddy-currents in response to the action of field-magnets as will hereinafter appear, and which is generally designated by the reference character 12.

The rotary armature 12 is rotatable electromagnetically from a predetermined normal "at rest" position, shown particularly well in Fig. 4, through a "first stage" of its operating movement, at the end of which it is momentarily arrested by an electromagnetic armature-stop lever which is generally designated by the reference character 13.

The rotary armature 12 before referred to, is provided with means for imparting thereto a rotational-bias, which preferably operates by gravity, to retain the said rotary armature in its predetermined normal "at rest" position between recurring impulses, in readiness to be again turned by another impulse.

As shown particularly well in Fig. 1, the rotary armature 12 is rigidly carried by an armature-

shaft 14 which is connected by a suitable drive connection to a center- or minute-arbor 16 of the timepiece as will hereinafter be described.

The movement-frame 10 comprises a front movement-plate 17, a rear movement-plate 18, and pillars 19 which are interposed between and rigidly secured to both of the said movement-plates 17 and 18 by screws 20.

The field-structure 11 includes a U-shaped magnet-yoke 21 which is formed of iron or the like and includes a crossbar 22 by means of which it is rigidly mounted on the rear face of the front movement-plate 17 and laterally-spaced side-bars 23 and 24. Rigidly mounted upon the side-bar 23 are two corresponding field-magnets 25—25, each of which includes an energizing-coil 26 having a pair of lead-wires 27—27 suitably connecting the two field-coils in series to each other and to line-wires 27a and 27b leading from a master clock (not shown).

As shown particularly well in Figs. 3 and 4, each of the field-magnets 25—25 also includes a pole-piece 28a formed of magnetic material which is secured at one end to the side-bar 23 of the magnet-yoke 21, each of the said pole-pieces being provided at its free end with a substantially-diametrical slot 28. The free end of each of the pole-pieces 28a terminates sufficiently short of the side-arm 24 of the magnet-yoke 21 to provide a sufficient space to accommodate the before mentioned rotary armature 12.

The diametrical slot 28 in the free end of each pole-piece 28a receives the straight bar-portion 29 of a suitable shading-coil 30 formed of copper or the like, to provide an unshaded salient pole 31 and shaded salient pole 32, the latter being encircled by the said shading-coil 30. According to Figs. 3 and 4, the shaded salient poles 32—32 are displaced in a counterclockwise direction with respect to the unshaded salient poles 31—31 around the peripheral edge-portion of the rotary armature 12. As thus arranged, when the field-magnets 25—25 are energized, rotating field-effects will result and the rotary armature 12 will be rotated in a counterclockwise direction as viewed in the figures above referred to, due to the eddy currents formed therein.

As shown particularly well in Figs. 1, 3 and 4, a stabilizing-arm 33 is mounted on the outer end of the armature-shaft 14 and is secured in position thereon by means of a set-screw 34. Movable radially upon the arm 33 is a weight 35 which may be secured in any desired adjusted position by means of a set-screw 36. The said weight 35 imposes on the armature 12 a gravitational-bias which tends to turn the said armature into and to return the same to a predetermined normal "at rest" position in a manner as will hereinafter appear. The armature 12 is provided with a radially-projecting stop-finger 37 which is adapted to be engaged with and released by the armature-stop lever 13, as will presently appear.

For the purpose of momentarily halting the rotational movement of the rotary armature 12 at the end of a "first stage" movement thereof, the said armature-stop lever 13 is preferably made of the bent-lever type and comprises a stop-lever arm 38, an intermediate bearing-loop 39 receiving and turning upon a pivot-pin 40 carried by the U-shaped magnet-yoke 21, and a depending resilient limiting-arm 41. An inverted U-shaped leaf-spring 42 carried by the crossbar 22 of the magnet-yoke 21 is interposed between

the limiting-arm 41 and said crossbar 22, as is shown particularly well in Figs. 3 and 4.

The said armature-stop lever 13 is preferably formed of soft steel or other non-permanent magnetic material, and is provided at one side adjacent its free end, with a stop-arm 43 terminating in a stop-finger 44 which is adapted to cooperate with the radially-projecting stop-finger 37 of the rotary armature 12, in a manner as will more fully hereinafter appear. The free end of the stop-lever arm 38 is curved rearwardly and downwardly to provide an actuating-arm 45 reaching within the field of influence of the field-magnets 25—25.

The armature-shaft 14 is journaled in two spaced-apart bearing-arms 46—48 bent rearwardly from the rear movement-plate 18 and on opposite sides of the vertical-longitudinal plane of the center-arbor 16. Mounted upon the armature-shaft 14, between the respective bearing-arms 46—48, is a worm 49 which is provided with a hub-portion 50 secured to the armature-shaft 14 by a set-screw 51. The hub-portion 50 of the worm 49 is arranged in axial abutment with the left-hand bearing-arm 46 (as viewed in Fig. 1), while a collar 52, which is secured to the armature-shaft 14, is in axial abutment with the right-hand bearing-arm 48. Secured to the center-arbor 16, adjacent the rear end thereof, is a worm-gear 53 which is constructed and arranged to intermesh with the worm 49 for the purpose of transmitting rotational impulses from the rotary armature 12 to the center-arbor 16.

As shown particularly well in Figs. 3 and 4, the center-arbor 16 extends through the front movement-plate 17 and carries at its forward end a minute-hand 54. Fastened to the center-arbor 16, adjacent the rear face of the front movement-plate 17, is a minute-pinion 55 which meshes with and drives a dial-wheel 56 secured to a dial-pinion 57 and journaled therewith upon a stud 58 extending rearwardly from the front movement-plate 17. The dial-pinion 57 meshes into an hour-wheel 59 interposed between the front movement-plate 17 and the minute-pinion 55. The said hour-wheel 59 carries a forwardly-extending hour-sleeve 60 which carries at its forward end an hour-hand 61.

For the purpose of making clear the operation of the impulse clock above described and illustrated in Figs. 1 to 6 inclusive, let it be assumed that the parts occupy the positions in which they are shown in Fig. 4, which may be said to be the normal "at rest" positions, inasmuch as at this time the mechanism has temporarily suspended active functioning and is awaiting the next periodic impulse from a suitable master clock. The impulses from the master clock, as just referred to, may be assumed to occur and reoccur once a minute.

When an impulse is received simultaneously by both of the field-magnets 25—25, a rotating field-effect will be developed by the field-structure 11 and the rotary armature 12 will be urged to turn in the direction indicated by the arrow A in Fig. 4 at a relatively-slow rate of movement such, for instance, as at the rate of one revolution in five or six seconds, though the rate of turn may be slower or faster as desired, provided only that, in the particular structure shown, the said rotary armature 12 completes its single rotational movement in response to a given impulse from the master clock prior to the time when a succeeding impulse is due from the master clock.

At the same time that the field-magnets 25-25 are energized and turn the rotary armature 12 as described, the stop-lever 13 will have its actuating-arm 45 attracted by the field-magnets 25-25, with the result that the said stop-lever will swing downwardly into the position in which it is shown particularly well in Fig. 3, to thereby interpose its stop-finger 44 in the path of movement of the stop-finger 37 of the rotary armature 12, to momentarily halt the same at the end of what may be aptly termed a "first stage" movement of its operation.

As the rotary armature 12 is thus brought to a halt at the end of the said "first stage" movement of its operation, the radial arm 33, with the weight 35 carried thereby, occupies the position shown particularly well in Fig. 3, and in this position imposes on the rotary armature a gravitational- or rotational-bias tending to effect a further continued rotational movement of the armature.

When the field-magnets 25-25 are deenergized, the stop-lever 13 is released from the attractive force of the field-magnets 25-25 and is thereupon raised by the pressure of the U-shaped leaf-spring 42 on the limiting-arm 41, the upward movement of the said stop-lever 13 being arrested by the engagement of the limiting-arm 41 with a stop-pin 41a. This upward movement of the stop-lever 13 serves to remove the stop-finger 44 from the path of the stop-finger 37 on the rotary armature 12, which latter is thus released for a "second stage" rotational movement which is effected by means of the weight 35 which moves downwardly under the action of gravity from the position in which it is shown in Fig. 3 to a position in which it depends from the rotational axis of the rotary armature to gravitationally stabilize the said armature in its normal "at rest" position, as particularly well shown in Fig. 4.

From the foregoing, it will be apparent that the stop-lever 13 serves to arrest the rotation of the armature 12, after the field-magnets 25-25 have effected the "first stage" rotational movement of the said armature, until the said field-magnets are deenergized whereupon the weight 35 effects the further rotation of the armature 12 to thus complete one revolution of the said armature to correctly register the time-indicating means with the indicia on the dial. It will thus be understood that each complete rotation of the rotary armature 12 as above described, will transmit a movement equivalent to one minute of time, to the hour-hand 61 and minute-hand 54 through the worm 49 and worm-gear 53.

The weight 35 during the "second stage" of rotational movement of the armature 12 as above described, serves to rotate the latter after the release thereof by the stop-lever 13, a degree sufficient to bring the stop-finger 37 of the said armature out from beneath the stop-finger 44 of the stop-lever 13 to thus insure the rotary armature 12 being free to again be effected for rotation by the field-structure 11, when the latter again receives an impulse from the master clock for advancing in step-by-step movement the hour-hand 61 and minute-hand 54 one minute of time-indicating distance.

In the modified form of the invention shown in Figs. 7 and 8, the movement-frame comprises a front movement-plate 63, a rear movement-plate 64, and spacing-pillars 65. Mounted on and supported by the rear movement-plate 64, is a field-structure, generally designated by the reference

5 character 66. The said field-structure 66 is generally similar in construction to that shown in Figs. 1 to 4 inclusive but, as shown particularly well in Fig. 7, is disposed substantially in a vertical plane and spaced rearwardly from the rear movement-plate 64. For this purpose, the field-structure 66 is supported by a horizontal arm 67 which extends rearwardly from the upper end of a vertical plate 68 secured to the rear movement-plate 64. The said field-structure 66 includes two corresponding field-magnets 69-69 having energizing-coils provided with lead-wires 70-70 which connect the energizing-coils in series to each other and to line-wires 70a and 70b leading from a master clock (not shown).

10 As shown in Fig. 7, the pole-piece of each of the field-magnets 69-69 is provided with an unshaded salient pole 71 and a shaded salient pole 72. For this purpose, the straight bar-portion 73a 20 of a shading-coil 73 is mounted in a substantially-diametrical slot in the pole-piece of each of the field-magnets 69-69 in a manner similar to that in which each of the straight bar-portions 29-29 25 of the shading-coils 30-30 are mounted, as described in connection with Figs. 1 to 4 inclusive. A rotary armature 74, which is mounted upon an armature-shaft 75, drives a worm 76 fastened to the said armature-shaft, the said worm 76 being in mesh with a worm-gear 77 fixed to a center-30 or minute-arbor 78.

35 As shown in Fig. 7, the center-arbor 78 extends through the front movement-plate 63 and carries at its forward end a minute-hand 79. Fastened to the center-arbor 78, adjacent the rear face of the front movement-plate 63, is a minute-pinion 80 which meshes with and drives a dial-wheel 81 secured to a dial-pinion 82 and journaled therewith upon a stud 83 extending rearwardly from the front movement-plate 63. The dial-pinion 82 40 meshes with an hour-wheel 84 interposed between the front movement-plate 63 and the minute-pinion 80. The said hour-wheel 84 carries a forwardly-extending hour-sleeve 85 which carries at its forward end an hour-hand 86.

45 According to the embodiment shown in Figs. 7 and 8, the rotary armature 74 comprises a composite structure by means of which it is rendered rotationally responsive to the rotary field-effects produced by the periodic impulses from the master clock in the field-structure 66 for imparting thereto its "first stage" movement; electromagnetically responsive to the field-magnets 69-69 for the purpose of momentarily arresting the said armature at the end of its "first stage" of movement; and gravitationally responsive to the force of gravity for turning the said armature through its "second stage" of movement.

50 For this purpose, in the embodied form of the invention, the rotary armature 74 which, in the main, is constructed of aluminum or other suitable non-magnetic material, has a segmental marginal portion thereof removed to receive a segmental plug 87 of the same size and shape, constructed of magnetic material. The said segmental plug 87 55 is fitted into the segmental opening formed in the outer marginal-portion of the rotary armature 74 and fastened therein in any suitable manner.

50 When an impulse from the master clock is received simultaneously by both of the field-magnets 69-69, a rotating field-effect will be developed by the field-structure 66, which will turn the rotary armature 74, in the direction of the arrow B to move the magnetic-plug 87 toward the right and upwardly, according to Fig. 7. As the

said magnetic-plug 87 passes its upper dead-center and moves toward the left, according to Fig. 7, it comes into the field of influence of the field-magnets 69-69 and is finally arrested in centralized relation thereto by the "lock-in" effect produced by the said field-magnets at the end of the "first stage" of the armature's operating movement. In other words, the magnetic-plug 87 is constructed and arranged to momentarily arrest the rotary armature 74 at the end of its "first stage" of operating movement and, after each deenergization of the field-magnets 69-69, to impart a rotational- and, in the present instance, a gravitational-bias to the said armature for moving it through its "second stage" of operating movement.

For these purposes, the magnetic-plug 87 may be constructed of soft iron or other suitable non-permanent magnetic material, and is made of sufficient size to secure an effective "lock-in" effect with the magnetic field of the field-magnets 69-69. As thus formed, the magnetic-plug 87 will also provide sufficient weight to impart the said "second stage" rotational movement to the said armature from its momentarily-arrested position, at the end of the "first stage" of armature movement, to the end of the latter's movement-cycle and into its normal "at rest" position, as is particularly well shown in Fig. 7.

In its normal "at rest" position, according to Fig. 7, the magnetic-plug 87 serves to stabilize, in their normal "at rest" positions, the rotary armature 74 and the time-indicating mechanism connected thereto.

During the "first stage" movement of each movement-cycle of the rotary armature, the magnetic-plug 87 is carried upwardly in a counterclockwise direction (according to Fig. 7), past its upper dead-center until it is disposed in the magnetic field of the field-magnets 69-69, by which it is arrested and with which it is electromagnetically interlocked until the said field-magnets are deenergized. As soon as this deenergization of the field-magnets occurs, the magnetic-plug 87 serves merely as a weight to impart a rotational-bias to the armature, which latter is thereby moved downwardly through its "second stage" movement into, and stabilized in, its normal "at rest" position.

As clearly shown in Fig. 7, the field-structure 66 of the motor-structure is arranged at a distance from the magnetic-plug 87, in the latter's normal "at rest" position, to render the rotary field-effects on the rotary armature 74 predominant over any electromagnetic attraction of the field-magnets 69-69 for the said magnetic-plug 87.

It will be understood from the foregoing that each complete rotation of the rotary armature 74 effects, through the worm 76 and worm-gear 77, the advancement of the hour-hand 86 and minute-hand 79 one minute of time-indicating distance to thus correctly register the time-indicating means with the indicia on the dial.

The duration of periodic impulses from the master clock need not be prolonged beyond a period sufficient to impart the "first stage" rotational movement to a quietly-rotating armature. At the completion of the "first stage" of rotational movement, the said armature is further rotated by a rotational-bias to complete one revolution of the said armature, which turns in synchronism with the time-pointer set of the timepiece and may be connected thereto by a continuous slow-moving gearing, such as worm-

gearing, which renders the operating-connections self-locking against all but the normal actuating-movements transmitted by the rotary armature.

The use of a motor-structure of the eddy-current type conduces to the production of a comparatively-inexpensive impulse-timepiece movement which is quiet and reliable in operation and comprises a relatively small number of parts of simple and effective form, which may be operated by pulsating or alternating currents of commercial frequencies such, for example, as 25, 50 and 60 cycle currents which may be preferably, reduced to 24 volts.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. An impulse-timepiece movement, comprising: a time-indicator; a field-structure including a field-coil and constructed to be energized by periodic electrical impulses; a rotary armature constructed and arranged to have eddy currents generated therein by the energization of said field-structure and to be periodically rotated through a first-stage of its operating movement by the electromagnetic reaction between said eddy currents and the said field-structure, the relationship between the said field-structure and the said rotary armature producing an electromagnetic reaction of substantially-constant value during at least the major portion of the energized phase of the said field-structure; means movable in the said first-stage movement of the rotary armature and rendered operative by the deenergization of the said field-structure for additionally rotating the said armature through a second-stage of its movement; and operating-connections between said rotary armature and said time-indicator.

2. An impulse-timepiece movement, comprising: a time-indicator; a field-structure including a field-coil and constructed to be energized by periodic electrical impulses from a remote source and generating rotary field effects, the said field-structure being positioned in electrical-influencing relationship with respect to a rotary armature to exert a rotary effect thereon; a rotary armature constructed and arranged to have a first-stage of its operating movement periodically imparted thereto by the rotary field effects, due to the energization of said field-structure, the said rotary field effects having a substantially-constant value during at least the major portion of the energized phase of the said field-structure, the said rotary armature having a second-stage of its operating movement imparted thereto by a rotational-bias due to the first-stage of its operating movement; and operating-connections between said rotary armature and the said time-indicator.

3. An impulse-timepiece movement, comprising: a time-indicator, a field-structure including a field-coil and constructed to be energized by periodic electrical impulses; a rotary armature constructed and arranged to have eddy currents generated therein by the energization of said field-structure and to be periodically rotated through a first-stage of its operating movement by the electromagnetic reaction between the said

eddy currents and the said field-structure, the relationship between the said field-structure and the said rotary armature producing an electromagnetic reaction of substantially-constant value during at least the major portion of the energized phase of the said field-structure; means electromagnetically responsive to the said field-structure for terminating the said first-stage of the operating movement of said armature; and means rendered operative by the deenergization of the said field-structure for imparting to said armature a second-stage of its operating movement; the said means being constructed to terminate the said second-stage of the armature's movement in a position corresponding to a predetermined position of said time-indicator.

4. An impulse-timepiece movement, comprising: a time-pointer set; a field-structure including a field-coil and constructed to be energized by periodic electrical impulses; a rotary armature constructed and arranged to have eddy currents generated therein by the energization of said field-structure and to be periodically rotationally displaced by electromagnetic reaction between said eddy currents and the said field-structure; means energized by said field-structure for predetermining the extent of and terminating a first-stage movement of the armature from a predetermined "at rest" position thereof; means carried by and imposing upon said armature a rotational-bias tending to further turn the armature for completing its movement-cycle, said rotational-bias being rendered operative by the deenergization of said field-structure; and operating-connections between said rotary armature and said time-pointer set.

5. A secondary impulse-timepiece having an operating motor-structure of the eddy-current type, the said motor-structure comprising a field-structure having shaded and unshaded salient poles and generating rotary field effects, the said field-structure being positioned in electrical-influencing relationship with respect to a rotary armature to exert a rotary effect thereon; a rotary armature constructed and arranged to be periodically rotated by the rotary field effects produced by said field-structure thereon and provided with a stop-finger; and a magnetic stop-lever movable by the energization of the said field-structure into the path of said stop-finger to arrest the armature at the end of a first-stage movement thereof, said rotary armature being provided with means to impart thereto, in its arrested position, a gravitational-bias which is rendered operative by the deenergization of the said field-structure to complete the movement-cycle of said rotary armature; and operating-connections to be interposed between the rotary armature and the time-pointer set of the impulse-timepiece.

6. A secondary impulse-timepiece having a motor-structure of the eddy-current type for driving the time-indicator of the timepiece and comprising a field-structure including a field-magnet provided with shaded and unshaded salient poles and generating rotary field effects, the said field-structure being positioned in electrical-influencing relationship with respect to a rotary armature to exert a rotary effect thereon; a rotary armature constructed and arranged to be periodically turned by the rotary field effects produced by said field-structure and having a stop-finger; a magnetic stop-lever movable into the circular path of the said stop-finger by the energization of the said field-structure to arrest

the armature at the end of a first-stage movement thereof from a predetermined "at rest" position of said armature; and a weight movable by and imparting to said rotary armature, in its position at the end of its first-stage movement, a rotational-bias for imparting a second-stage movement thereto, said weight being arranged to depend below the axis and in the axial plane of the rotary armature at the end of its said second-stage movement.

7. A secondary impulse-timepiece movement having a time-indicator and means for transmitting a step-by-step movement thereto, the said movement-transmitting means including a motor of the eddy-current type comprising: a field-structure including a field-magnet for receiving periodic electrical impulses from a master clock and generating rotary field effects, the said field-structure being positioned in electrical-influencing relationship with respect to a rotary armature to exert a rotary effect thereon; a rotary armature constructed and arranged to be periodically turned by the rotary field effects produced by said field-structure, said rotary armature being provided with a marginal segmental portion constructed of magnetic material arranged to stabilize the rotary armature in a normal "at rest" position when the said field-structure is deenergized and to impart a rotating-bias to the rotary armature at the end of a first-stage of the armature's operating movement, the said marginal segmental portion of the rotary armature being arranged to terminate the said first-stage movement thereof by its electromagnetic "lock-in" arrangement with respect to the energized field-structure and rendered gravitationally operative by the deenergization of the said field-structure to impart an additional turning movement to the armature to complete a movement-cycle of the same and to stabilize it in its normal "at rest" position.

8. A secondary impulse-timepiece movement, comprising: a time-pointer set; an actuating-spindle therefor; a motor of the eddy-current type including a field-structure having a field-magnet constructed to be energized from a master clock and generating rotary field effects, the said field-structure being positioned in electrical-influencing relationship with respect to a rotary armature to exert a rotary effect thereon and a rotary armature constructed and arranged to be periodically actuated by the rotary field effects of said field-structure; means electromagnetically-responsive to the energization of said field-structure for arresting the rotary armature at the end of a first-stage of its operating movement; and means movable in the said first-stage movement of the rotary armature to impart a rotational-bias thereto, the last said means being rendered operative by the deenergization of the said field-structure to complete the movement-cycle of the rotary armature and to stabilize it in a normal "at rest" position corresponding to a predetermined position of the time-pointer set, the said rotary armature being connected to the actuating-spindle for the time-pointer set.

9. A secondary impulse-timepiece movement, comprising: a time-indicator; a field-structure constructed to receive periodic electrical impulses from a master clock and generating rotary field effects, the said field-structure being positioned in electrical-influencing relationship with respect to a rotary armature to exert a rotary effect thereon; a rotary armature constructed and arranged to be periodically turned by the rotary

field effects of said field-structure, through a "first stage" of its operating movement from a normal "at rest" position corresponding to a predetermined position of the time-indicator and provided with means movable in the said "first stage" of its operating movement to impose thereon a rotational-bias tending to effect a "second stage" rotational movement of the said armature; and means operated by the energization of said field-structure for momentarily arresting the rotational movement of the rotary armature at the end of said "first stage" movement thereof and releasable by the deenergization of the field-structure to effect the said "second stage" of rotational movement of the rotary armature by the action of said rotational-bias; the said bias-creating means being constructed and arranged to terminate the said "second stage" movement and to complete an operating-cycle of the rotary armature for each periodic electrical impulse received by the said field-structure.

10. A secondary impulse-timepiece movement, comprising: a time-indicator; a field-structure constructed to receive periodic electrical impulses from a master clock and generating rotary field-effects, the said field-structure being positioned in electrical-influencing relationship with respect to a rotary armature to exert a rotary effect thereon; a rotary armature constructed and arranged to be moved by the rotary field-effects of said field-structure when energized, through a "first stage" turning movement from a normal "at rest" position corresponding to a predetermined position of the time-indicator; a weight movable by the rotary armature and being in eccentric relation to the rotary axis thereof and arranged to depend in the vertical axial plane of the rotary armature in the said normal "at rest" position thereof; means operated by the energization of said field-structure for momentarily

arresting the rotational movement of the rotary armature after the eccentrically-mounted weight has been raised to and moved past the upper dead center of its movement into a position in which, at the end of the said "first stage" movement of the rotary armature, it imparts a rotational-bias to the rotary armature, the said armature being released by the deenergization of the field-structure to effect a "second stage" rotational movement thereof under the action of said rotational-bias, the arrangement of the said eccentrically-mounted weight being adapted to terminate the said "second stage" movement thereof in the normal "at rest" position of the said rotary armature.

11. A secondary impulse-timepiece movement, comprising: a time-indicator; a field-structure constructed to receive periodic electrical impulses from a master clock and generating rotary field-effects, the said field-structure being positioned in electrical-influencing relationship with respect to a rotary armature to exert a rotary effect thereon; a rotary armature constructed and arranged to be periodically moved by the rotary field-effects of the field-structure through a "first stage" rotational movement from a normal "at rest" position corresponding to a predetermined position of the time-indicator; a magnetic-plug carried by the rotary armature and arranged to be electromagnetically locked with the said field-structure for momentarily arresting the rotary armature at the end of its said "first stage" operating movement and to impart a gravitational-bias tending to effect a "second stage" of the operating movement of the rotary armature, said rotary armature being released by the deenergization of the said field-structure to effect the said "second stage" of its operating movement.

WEYMAN E. MAXWELL.
